(No Model.)

C. W. SHEDD.
CAN FILLING MACHINE.

No. 510,652.

Patented Dec. 12, 1893.

UNITED STATES PATENT OFFICE.

CHARLES W. SHEDD, OF GRAND RAPIDS, MICHIGAN.

CAN-FILLING MACHINE.

SPECIFICATION forming part of Letters Patent No. 510,652, dated December 12, 1893.

Application filed October 14, 1892. Serial No. 448,872. (No model.)

To all whom it may concern:

Be it known that I, CHARLES W. SHEDD, a citizen of the United States, residing at Grand Rapids, in the county of Kent and State of Michigan, have invented certain new and useful Improvements in Can-Filling Machines; and I do hereby declare the following to be a full, clear, and exact description of the invention, such as will enable others skilled in the art to which it appertains to make and use the same.

My invention relates to improvements in can filling machines, and its object is to provide the same with certain new and useful features, hereinafter more fully described and particularly pointed out in the claims reference being had to the accompanying drawings, in which—

Figure 1 is a central vertical section (on the line 1—1 of Fig. 2) of a device embodying my invention; Fig. 2 a front elevation of the same; and Fig. 3 a detail (in vertical section) of the salt feeder.

Like letters and numerals refer to like parts in all of the figures.

A represents the bed plate upon which are secured two parallel guides, or ways B B, having grooves B' in which moves the slide C, which slide vibrates beneath the vertical can chute, and moves the lower can E forward a distance equal to its diameter, to the position of the can E', which latter can in turn moves the preceding can forward to the position of the can E''; said cans being guided and kept in line by said ways B B.

D is the rear wall of the vertical can chute, which wall terminates above the table A at sufficient distance to permit the slide C to pass. D' is the forward wall of said chute, which together with another parallel wall D'' comprises the front and rear walls of a salt chamber, which chamber is closed at the bottom, and is sufficiently above the table to let the cans pass beneath the same. In the bottom of said chamber is an opening directly above the opening in the can E', and in said opening is the lower end of a plunger K, which plunger fits said opening and is vertically movable therein. Said plunger K has a groove K' in one side, terminating in an inclined plane at the lower end near the end of the plunger K. In this groove is a strip L which

fills the same except a short distance at each end, and said strip is longitudinally adjustable and secured by a thumb nut and bolt L', whereby the chamber formed by the lower end of the groove K' may be adjusted to contain more or less salt, which is placed around said plunger K, and which is broken up and caused to fall into said lower end of the groove K, by a series of pins O on said plunger, which terminates in a stem M, which stem passes through a guide (not lettered), and around said stem is a spring which restores the plunger to the elevated position shown, after it has been depressed by the arm P'. A hopper F is secured directly above the can E'' by bolts J passing through slots J' J'' in the wall D''. Said bolts also secure guides I I in which is a vertically movable piston H', having attached a head II, which head moves vertically within the lower part of said hopper, and also passes downward within a cylindrical extension F'' at the lower end of said hopper which extension at its lower end terminates in a nozzle T of reduced diameter to enter the opening in the top of the can E'' and is surrounded with a cylinder or casing F''', having an outwardly flanged lower end faced with an elastic packing. This casing and packing retains the air and surplus that escapes around the nozzle T, from whence they are conveyed away by a pipe U attached to and opening into said casing. An adjustable strainer F' is provided near the bottom of the hopper F, consisting of a sheet metal piece fitted upon the surface of the hopper and adjustable thereon, said sheet metal and the hopper having perforations that will coincide when the movable piece is adjusted in middle position, and which may be also partially or wholly opened by adjusting said piece of sheet metal. Beneath this strainer is a trough G to receive the liquid passing through the strainer, which liquid is conveyed away by the pipe U', attached to and opening into said trough G.

Beneath the can E'' is a vertically movable piston V, having a roll V' projecting from its lower side, and engaging a cam X on the driving shaft W. Said cam raises the piston V during the greater part of the revolution of the shaft and presses the can E'' upward against the packing S while it is being filled by the

descent of the piston H. Said shaft W is journaled in suitable hangers 9, 9 beneath the table A and is provided at one side with a crank wheel 7 and at the other side with a crank bend W', to which cranks are connected rods R, which extend upward at each side of the machine and connect to the respective ends of a yoke Q through which passes the piston rod H' provided with nuts H'' at each side of said yoke to vertically adjust said piston therein.

To operate the slide C a rock shaft 2 is journaled in suitable hangers 5, 5, and provided with an arm 6 extending toward the driving shaft and provided with a roll 10 which engages a cam V adjustably secured upon the side of the cam wheel X by means of a bolt Z passing through said wheel, and a curved slot Y' in said cam. Another arm 6' extends upward from said rock shaft and is connected at its upper end to the slide C by means of the rod 8, having a series of holes whereby its working length may be adjusted, whereby the slide C will move farther forward and will place smaller cans in proper position and by adjusting the hopper and by moving the bolts J in the slots J' cans of various heights may be filled.

At the rear of the yoke Q is an arm P, which passes through and traverses the vertical slot J'' in the wall D'' and prevents the turning upon its axis of the piston H'. On this arm is a detachable extension P', which as it descends strikes stem M on the plunger K and depresses said plunger, which is again restored to place by the spring N surrounding said stem. By extending the yoke Q and crank shaft W and providing a wider can chute, salt chamber and two plungers and a wider lower extension F'', together with a wider piston H, and wider ways B, the capacity of the machine may be doubled without duplicating the entire machine. If desirable the crank bend W' may be replaced by a crank disk as at the other side, and both disks provided with crank pins in slotted openings whereby the stroke of the piston may be adjusted; in this case one or both of said disks may be provided with a cogged edge and the machine driven by a pinion engaging said cogs and suitably mounted on a driving shaft.

The operation of my device is as follows: At each revolution of the driving shaft the bottom can in the chute is moved forward, and the column of cans in the same move down, the can assuming the position shown in Fig. 1. The position of the parts is shown as at the end of this movement. The enlarged side of the cam wheel X now raises the forward can firmly against the packing S, with the nozzle T in the opening of the can where it is held during about three fourths of the revolution of the shaft W. The piston H at once rises above the bottom of the hopper F, allowing the contents of said hopper to fall into the cylindrical extension F''. The piston then descends and forces said contents down

into the can through the nozzle T. As the piston starts on its return stroke, the smaller part of the wheel X reaches the roll V' and allows the piston V to descend to the position shown. While the can is being filled the roll 10 traverses the cam Y to its smaller side, thus allowing the spring 4 to retract the slide C from beneath the cans in the chute. By its forward movement the lower can E is now thrust forward, moving the filled can out to the front of the table and placing the next can in position. In the meantime the middle can of the lower series stops beneath the salt receptacle, and as the piston descends the arm P' strikes the extension M and drives the plunger K down through the bottom discharging the salt in the lower end of the groove K' into said can, these described movements being repeated in succession as long as cans are applied to the chute and salt to the middle receptacle and materials to fill the cans to the hopper. To disconnect the salt feed, the extension P' is removed from the arm P. The plunger K will then remain stationary.

What I claim is—

1. In combination with a hopper, extension, and vertically movable plunger, a salt receptacle, a movable plunger in the same, having a chamber in its side and operated by said plunger, substantially as described.

2. In a can filling machine, having a movable plunger to fill the cans, a salt chamber and a movable plunger in the same, and passing through the bottom thereof, a groove in the side of the plunger, and a strip filling a part of said groove and adjustable therein, and projection on said plunger, substantially as described.

3. In a can filling machine in combination with a can filling mechanism, having a vertically movable cross head having a plunger attached, an arm on said cross head, a detachable extension on said arm, a plunger engaged by said extension, a spring on said plunger, a chamber in the side of said plunger, a salt receptacle surrounding said plunger, and an opening in the bottom of said receptacle, through which said plunger passes, substantially as described.

4. In a can filling machine, a salt receptacle, having slotted openings in its side, a hopper having cylindrical extension, and adjustably secured by bolts passing through said slotted openings, a cross head above said hopper and a can lifter below the same, both having a fixed stroke, an arm on said cross head engaging a slot in the salt receptacle, a detachable extension on said arm, a plunger in said salt receptacle passing through the bottom of the same, and engaged by said extension, and a piston having a rod passing through said cross head and adjusting nuts on said rod, substantially as described.

5. In a can filling machine, in combination with a can chute, a hopper, a plunger, and a slide to feed the cans from the chute to the

filling mechanism, mechanism for adjusting the stroke of said slide to feed cans of various diameters, substantially as described.

6. In a can filling machine, in combination with a hopper, a cylinder, a piston and a reciprocating cross head; a piston rod having adjustable nuts engaging the respective sides of said cross head, a vertically slotted support, for said cylinder and hopper, and bolts passing through said slots, whereby the device may be adjusted to cans of different heights, substantially as described.

7. In a can filling machine, in combination with a can chute, can filling mechanism, and

ways beneath the same, a slide between said ways, a pivoted lever and means for vibrating said lever, a connecting rod between said lever and slide, said rod having a series of openings, whereby the stroke of said slide may be adjusted to cans of various diameters, substantially as described.

In testimony whereof I affix my signature in presence of two witnesses.

CHARLES W. SHEDD.
